UNITED STATES PATENT OFFICE.

OSCAR H. LUDEMAN, OF GLEN RIDGE, NEW JERSEY.

BOILER-FEED-WATER SYSTEM.

Application filed March 12, 1923. Serial No. 624,417.

To all whom it may concern:

Be it known that I, OSCAR H. LUDEMAN, a citizen of the United States, residing at 114 Hillside Avenue, Glen Ridge, New Jersey, 5 have invented certain new and useful Improvements in Boiler-Feed-Water Systems, of which the following is a specification.

My invention relates to a new and improved water supply system, particularly 10 adapted to supplying feed water to steam boilers and to a construction and combination of parts adapted to control such supply automatically.

The object of the invention is to provide a 15 water supply system which in its application to boiler feeding will dispense with injectors, boiler feed pumps and dumping or tilt traps with their more or less complicated parts, the system being continuously and automatically operated, and requiring the minimum of personnel and labor.

In practice where the water of condensation or water supply is delivered below the water level in the boilers it is necessary, 20 with other forms or systems, to raise the water when feeding to the boilers by means of pumps, two or more tilt or dumping traps, or injectors, involving more complicated mechanism or high steam consumption, or both. In accordance with my invention much apparatus is dispensed with. A very simple mechanism is employed, and the steam required for operating is relatively small. A reservoir is placed above the boiler 25 water level, another is placed at a point sufficiently low to receive the returns of condensation and makeup water for supplying the boilers. A water supply pipe connects the upper with the lower tank or reservoir; another water supply pipe or pipes connects 30 the upper tank with the boiler or boilers being supplied. One tank, known as the controlling tank, is provided with a float, a float arm, together with the necessary connections and valves forming the distributor. A high pressure steam line connects the distributor with the steam space in one or more 35 of the boilers. Another steam line connects the distributor in the controlling tank with the top of the other or controlled tank.

The invention provides means for supplying the water to the boilers automatically, the operation being governed by the float in the controlling tank, the water being alternately delivered by means of steam pressure 40 from the lower to the upper tank, and then

flowing by gravity from the upper tank to the boilers. In the particular embodiment of this improvement there is incorporated in the controlling tank a valve mechanism whose operation is controlled by a float. This valve mechanism comprises two valves, each having two seats, both these valves in this particular form of construction being on one stem, thereby moving together at all times. These valves, seats and mechanism comprise the distributor. The controlling tank with the distributor may be either in the upper or lower position with relation to the controlled tank as the conditions of the 45 installation may permit or warrant. The float controls the operation of the valves in the distributor thru a spring snap connection, giving a positive instantaneous movement of the valves in either direction. The 50 position of these distributor valves determines the alternate delivery of steam to and release of steam from the controlling and controlled tanks, respectively.

Thus means are provided whereby the upper tank is emptied and the lower tank filled, the float in the controlling tank actuating the distributor valves so that the steam previously admitted to the upper tank (which has just been emptied) is exhausted, thereby 55 relieving said upper tank of pressure, and at the same time high pressure steam is admitted to the filled lower tank, thus displacing the water in said lower tank, following which the change in the lever of the float in the controlling tank reverses the position of the distributor valves, releasing or exhausting the steam from the lower tank, permitting its refilling by the condensation returns or makeup water; at the same time steam under 60 pressure is admitted by the distributor to the upper filled tank, thereby creating a pressure in this upper tank equal to the boiler pressure, so that the water will flow by gravity from this upper tank to the boiler or boilers at a rate predetermined by the opening of the feed valves in the water supply lines to the respective boilers, the feed valves being controlled by the operator.

Means are thus provided comprising a controlled tank and a controlling tank with a balancing and pressure applying steam line between the tanks whereby the supply of water to one tank is automatically and intermittently delivered to the other tank 65 and the boiler supplied with water.

The two tanks are connected by a water

pipe and the balancing and pressure applying steam line and distributing valves being so controlled and operated as to supply steam pressure from the boiler and by means 5 of the steam line alternately to the upper and lower tanks, thereby alternately filling the upper tank from the lower tank.

It will be obvious that the water in the lower tank will be expelled and delivered 10 into the upper tank very quickly, due to the admission of high pressure steam to said lower tank, so that there need be no practical interruption to the continuity of flow of water from the upper tank to the boiler 15 or boilers.

A further improvement to this system is shown in one of the accompanying drawings, wherein in installations where the controlling tank is the upper tank, means are provided 20 in the lower tank or controlled tank, by the installation of a float controlling a water valve whereby if condensation returns are insufficient to take care of the requirements of the boilers so that the lower tank 25 is not filled equal to the amount of water leaving the upper tank to the boilers, the float in the lower tank will necessarily go to a lower position, thus admitting water from the general water supply system to this 30 tank to make up for the deficiency for the supply in the returns, thereby always insuring complete filling of the upper tank from the lower tank.

Further application of this feature just 35 described is also shown, whereby this automatic float controlling the water makeup supply, together with the lower tank, are both incorporated in the base of and form a part of a feed water heater, this construction making a more compact unit occupying less space without involving complications.

In the drawings attached to and forming part of the present specifications:

45 Fig. 1, is an elevation partly in section of the apparatus showing the float tank or controlling reservoir below the boiler-water level, filled and ready to deliver its supply to the controlled reservoir, this latter being 50 above the boiler-water level.

Fig. 2, is a vertical section thru the float-tank and its various connections, the parts being those illustrated in Fig. 1.

Fig. 3 is a vertical section thru the distributor or valve mechanism, in the position shown in Fig. 1.

Fig. 4, is a section along the line "a—a" of Fig. 3.

Fig. 5, is a section along "b—b" of Fig. 3, and

Fig. 6, a section along "c—c" of Fig. 3.

Figs. 7, 8 and 9 are detail views of the float controlled valve operating mechanism.

Fig. 10, shows a section similar to Fig. 1, but with the float tank above and the con-

trolled reservoir below the level of the water in the boiler and showing a supplemental feed supply for the water.

Fig. 11, is a view in section showing the float down, the parts being those illustrated 70 in Figure 10.

Fig. 12, is a vertical section showing a water heater and water supply system embodying the invention.

1 is the boiler into which discharges the 75 water feed pipe 2 and from which leads the pressure pipe 3. Reservoir 4, is provided, which is connected with the float tank 5, by the pipes 6 and 8 and with the boiler by pipe 2. The pipe 7 into which flows the 80 water of condensation, empties in Figs. 1 and 2, into the top of the float tank 5, and in Fig. 10, the corresponding pipe 7^a empties into the top of reservoir 4'. Enclosed within the tank 5 is the float 9 with its 85 lever arm fulcrumed at 11, operating the distributor, including the valve stem 12, the valves 13 and 14. This controls the pressure between the boiler 1, tank 5 and reservoir 4. An exhaust for tank and reservoir 90 is provided thru pipe 15.

Each valve has two operating faces so that, according to their position, these valves can put into communication or shut off communication between the pipes 3, 6 and 15, 95 and the passage 17 as will be described later on.

The pipe 3 leading from the boiler terminates opposite the valve 14. The pipe 15, 100 starting in front of the valve 13, communicates with the outside atmospheric pressure. Pipe 6, starting from the upper part of reservoir 4, terminates between the valves 13 and 14, and furnishes communication between tank and reservoir, alternately in two 105 directions. Besides the steam or exhaust pipes 3, 6 and 15, terminating in the body of the distributor, there is a water supply pipe 8, connecting the reservoir 4 and the tank 5, serving in Fig. 1 to transport water 110 from tank 5 to reservoir 4, or in Fig. 10, a similar water supply pipe 8^a, leads from reservoir 4' to tank 5. Finally a pipe 7 delivers the water of condensation to the top of tank 5, in Figs. 1 and 2, and a pipe 115 7^a to the top of the reservoir 4, in Fig. 10. Check-valves 16, 19, 20, working in the proper direction are provided in the various pipes.

Means are provided whereby the float 120 lever controls the actuation of the distributor so as to produce a snap action of the valves at two positions of the float, when the float tank is nearly full also when it is nearly empty.

In Figs. 7, 8 and 9, are shown the details of the spring operated mechanism by means of which the float lever controls the action of the valve rod 12 and the valves 13 and 14. The form of this spring may be varied as 125 130

illustrated. The float lever 10 is fulcrumed on the fixed point 11 and carries an eye 27 thru which passes a spring 26. The two free ends of the spring are connected to two freely oscillating rockers 28 and 29. The angular portions of these wedges engage in grooves fashioned in the piece 30 attached to the valve-rod 12, of the valves 13 and 14. The rod 12, carrying the two valves 13 and 14, is provided with two collars 31 and 32, and has at its two extremities nuts and set-nuts 33, 34, 35 and 36. It is also provided with a ring 37 and a conical ring 38, with guide rings 39. By means of these collars, nuts and rings, the positions of the two valves can be accurately controlled so as to fit and shut off the two lower seats 40 and 41, or open together the two upper seats 42 and 43.

Figure 9 shows in dotted lines all the parts in the median position which is a position of unstable equilibrium corresponding to the moment when points 27 and 11 are on the same horizontal line. If at this moment the float 9 rises slightly, the eye 27 rises and pushes upward the free ends 28 and 29, which oscillate and take a position as indicated at the right in Fig. 9, thereby forcing down the valve-rod 12, and seating the valves 13 and 14 on their lower seats 40 and 41.

Hence, when the float rises above the position where the lever 10 is horizontal, the rod 12 descends. It does not, however, descend so far as is indicated at the right of Fig. 9, but into the position shown in Fig. 7, where the two valves come to a stop on their lower seats, shutting them off, and are held applied to the seats by the pressure of the spring 26, resting in the holes of the wedges 28 and 29 and maintaining them in the position shown. If, on the other hand, the float 9 sinks below the position where its lever 10 is horizontal, the eye 27 sinks carrying down the extremities of the spring 26, lowering the holes 28 and 29 of the wedges, tilting them into the position indicated in Fig. 8 and at the left of Fig. 9, thus causing the rod 12 to rise and the valves to rest on their upper seats 42 and 43. Therefore, when the float descends below the position where lever 10 is horizontal, the rod 12 rises. The stroke of the rod in this direction is, however, shorter than that shown in Fig. 9, since this figure has been drawn exaggerating the throw of the wedges and to clearly illustrate the difference between Figures 7 and 8.

Referring to Fig. 3, the fulcrum 11 of the lever 10 of the float 9, is mounted in bracket 46. The bronze valve seats of the valves 13 and 14 and two long threaded pieces 47 and 48 permit the mounting of and the access to the movable parts and to the fixed seats of the distributor. The part

47 serves as guide for the rings 39, the part 48 having a polygonal head, assisting in its removal. It, moreover, forms a dome around the top of the valve rod 12, and allows communication between the upper 70 seat of the valve 14 and the passage 17, which ends in the top of the tank 5. The two branches of the passage 17 are accessible by removing the threaded plugs 49 and 49a.

The operation, as illustrated in Fig. 1, is 75 as follows: The valve 50 is open under the control of the operator. The float 9 in its ascent has brought down the valves 13 and 14 onto their lower seats 40 and 41. The boiler pressure is now transmitted thru pipe 3, passing above the valve 14, thru the passage 17 onto the surface of the water in tank 5. This closes the check valve 16 of the pipe 7, thru which the water of condensation comes into the tank. At the same time this pressure forces open the check valve 19 of the pipe 8, thru which the water passes to fill the reservoir. At this time the top of the reservoir 4, thru the pipe 6 which opens between the two valves 13 and 14 is in communication with the exhaust pipe 15, the pressure in pipe 6 acting in the direction of the full arrow; the boiler pressure keeps the valve 20 closed.

Figure 2 shows the operative parts of the tank 5, in a new position. The float 9 having fallen has raised the rod 12 bringing the valves 13 and 14 against their upper seats 42 and 43. Thereupon, the boiler pressure is transmitted thru the pipe 3, under valve 14, thru the pipe 6 to the surface of the water in the reservoir 4, placed above the boiler, into which it empties under the pressure in pipe 6, assisted by gravity, the direction of pressure in the pipe 6 being indicated by the dotted arrow. During this time the top of the tank 5 is connected thru the bottom of valve 13 with the exhaust 15, releasing the steam pressure, which allows the water of condensation to enter the tank 5, thru the valve 16, the pressure in reservoir 4 closing the valve 19.

Fig. 10, shows another arrangement of the parts, the tank 5' being now above and the reservoir 4' below the water level of the boiler. The tank is full, the float 9' up and the valves 13' and 14' on their lower seats. Pressure from the boiler passes thru the pipe 3' above the top of valve 14', thru the passage 17' onto the surface of the water in tank 5'. The check-valve 22' is open and water enters the boiler. At the same time the top of reservoir 4' communicates with the outer air thru pipe 6', the top of valve 13' and the exhaust 15', (the pressure decreasing in the direction of the full arrow). The water of condensation can now open the valve 21' and flow into the reservoir 4', the pressure of the boiler, exerted in tank 5', closing the valve 23'.

In the condition shown in Fig. 11, the float 9' is down, the valves 13' and 14' up. The boiler pressure now passes thru pipe 3', under the valve 14', thru the pipe 6', in the direction of the dotted arrow of Fig. 10 and acts on the surface of the water, which has entered the reservoir 4'. This pressure closes valve 21' shutting off the water of condensation, opens the valve 23', forcing the water from reservoir 4', into tank 5', which it fills. The tank 5' at this time is open to exhaust, thru the bottom of valve 13' and the pipe 15', the boiler pressure closing the valve 22'.

Means are provided in case the supply of water of condensation is insufficient, for supplying additional water. The latter may come from the city mains. Pipe 100 connected with a supplemental source of supply, like the city mains, is connected with the lower tank, a check valve 101 preventing back flow. A float 102 is connected with valve 103 so as to open the supply from the city mains, in case the water level of the lower tank sinks too low, i. e., in case the water of condensation supplied from the pipe 7^a is insufficient.

It is to be noted that in the two conditions of the installation shown in Figs. 1 and 10, it is the lower member, whether reservoir 4 or tank 5, that receives the water of condensation and, therefore, we can in the two cases reintroduce the water of condensation into the boiler. Whether the tank or the reservoir is to be placed above or below the boiler depends upon the conditions of the location of the installation.

The amplitude of the motion of the float 9 and the frequency of its action can be controlled by the location of the points 27 and 11, which can be more or less widely separated vertically or horizontally.

In Fig. 12, a water heater is illustrated in which there is provided an upper compartment 50' receiving water from pipe 51 which may be heated by pipe 52 supplied with exhaust steam. The water passes into the compartment first falling on baffle plates 53, 54 and passing into the lower compartment 55 thru valve 56. At the proper time, the water from lower compartment 55 is forced upwardly thru pipe 57 to the upper controlling tank 58, by steam pressure. After the upper tank 58 is filled and steam pressure from boiler 59 has been applied to the upper tank, the water flows from the upper tank into the boiler by pipe 60. The distributing valve system controlled by a float in the upper tank is like the one illustrated in Figs. 10 and 11 for example and described in the specification. The float 61 by snap spring connection (like that illustrated in Figs. 7 and 8) controls the valves 62, 63, which in turn control steam pressure pipe 64 (regulated by hand valve 65) ex-

haust pipe 67, steam connecting pipe 68, connecting the upper tank 58 with lower compartment 55. With the parts in the position shown in Fig. 12, steam pressure from the boiler passes thru pipe 64, then by way of the central valve port and pipe 68 (see full arrow) to the lower compartment 55, forcing the water in the lower compartment upward thru pipe 57 into the upper tank 58. Pressure in the upper tank is relieved by exhaust pipe 67. After the upper tank is filled, the float 61 rises and at the top of its movement, the float thru the spring snap connection reverses the position of the valves 62, 63 and lowers them against their lower valve seats. Steam under pressure from pipe 64 now passes thru valve port 63^a, thru bypass 63^b to the top of the upper tank. The steam pressure in the boiler and upper tank now being the same, the water flows into the boiler thru pipe 60 by gravity.

Means are provided for supplying additional water from the city mains or other supplemental supply, should the supply of the water of condensation to the lower compartment of the heater prove inadequate.

An auxiliary pipe 70 connected to a supplemental supply (not shown) is connected to pipe 71 leading to inlet pipe 51. Valve 72 is opened by bell crank 73 and float 74, by means of connection 75 when the water level drops to a predetermined level, i. e., when there is not sufficient water in the lower compartment.

Having thus described the invention it will be understood that changes may be made therein without departing from the principle of the invention.

What I claim and desire to secure by Letters Patent is:

1. In a water supply system, the combination of a controlled tank and a controlling tank, a steam pressure pipe line for supplying steam pressure to the controlling tank, a pipe between one of said tanks and the apparatus to be supplied with water, a mechanically controlled, balancing and pressure applying steam line for the controlled tank, a valve for controlling the flow of steam through the steam line, said valve also controlling a passage between the steam pressure pipe line and the controlling tank so as to admit pressure to or cut it off from the controlling tank, a water pipe line between the tanks, a float in the controlling tank, mechanical connections between the float and the valve, and means whereby said float in the controlling tank automatically, intermittently and mechanically controls the parts so as to supply water to the apparatus to be supplied.

2. In a water supply system for supplying feed water to boilers, the combination of a controlled tank and a controlling tank,

- a steam pressure pipe line for supplying steam pressure to the controlling tank, a pipe between one of said tanks and the boiler for supplying water to the boiler, a steam line for the controlled tank, a water pipe line between the tanks, and a float connected with said controlling tank, a distributor and mechanical connections between said distributor and said float, said distributor provided with a valve, which valve controls the steam line for the controlled tank and the steam pressure line for and passage to the controlling tank, thereby controlling the water supply to or from the controlled tank and to the boiler. 5
3. In a water supply system for supplying feed water to boilers, the combination of a controlled tank and a controlling tank, a steam pressure pipe line for supplying steam pressure from the boiler to the controlling tank, an exhaust pipe line communicating between the controlling tank and the atmosphere, a pipe between one of said tanks and the boiler for supplying water to the boiler, 10 a mechanically controlled steam line for the controlled tank, a valve for controlling the flow of steam through the steam line, said valve also controlling a passage between the steam pressure pipe line and the controlling tank so as to admit pressure to or cut it off from the controlling tank, a water pipe line between the tanks, a float in the controlling tank, mechanical connections between the float and the valve, and means whereby said float in the controlling tank automatically, intermittently and mechanically controls the parts so as to supply water to the boiler. 15
4. In a water supply system for steam boiler, the combination of a controlled tank and a controlling tank, a water line between the tanks, a steam line and connections for supplying steam pressure to the controlling tank, an exhaust line between the controlling tank and the atmosphere, a mechanically controlled steam line for the controlled tank, a feed water pipe between one of said tanks and the boiler, a float connected with the controlling tank and a distributing valve mechanically connected to said float for controlling the steam pressure supply line and its connection with the controlling tank, the steam line for the controlled tank and the exhaust line, thereby supplying water to or from the controlled tank and to the boiler. 20
5. In a water supply system for steam boilers, the combination of a controlled tank and a controlling tank, a steam line and connections for supplying steam pressure to the controlling tank, an exhaust line between the controlling tank and the atmosphere, a steam line for the controlled tank, a feed water pipe between one of said tanks and the boiler, a float connected with the controlling tank and the exhaust line, thereby supplying water to or from the controlled tank and to the boiler. 25
6. In a water supply system for steam boilers, the combination of a controlled tank and a controlling tank, a steam line and connections for supplying steam pressure to the controlling tank, a water line between the controlled and controlling tanks, a steam line for the controlled tank, a feed water pipe between one of said tanks and the boiler, a float connected with the controlling tank, a pair of valves, a valve stem carrying said valves, and connections between said valve stem and said float, said valves controlling the steam pressure supply line and its connection with the controlling tank, the steam line for the controlled tank and the exhaust line thereby supplying water to the controlled tank and to the boiler. 30
7. In a water supply system for steam boilers, the combination of a controlled tank and a controlling tank, a water line between the tanks, a steam line and connections for supplying steam pressure to the controlling tank, an exhaust line between the controlling tank and the atmosphere, a steam line for the controlled tank, a feed water pipe between one of said tanks and the boiler, a float connected with the controlling tank, a distributing valve mechanical connection including a lost motion connection between said valve and said float controlled by said float for controlling the steam pressure supply line and its connection with the controlling tank, the steam line for the controlled tank and the exhaust line, thereby supplying water to or from the controlled tank and to the boiler. 35
8. In a water supply system for steam boilers, the combination of a controlled tank and a controlling tank, a water line between the tanks, a steam line and connections for supplying steam pressure to the controlling tank, an exhaust line between the controlling tank and the atmosphere, a steam line for the controlled tank, a feed water pipe between one of said tanks and the boiler, a float connected with the controlling tank, a distributing valve for controlling the steam line and its connection with the controlling tank, said valve also controlling the steam line for the controlled tank, a spring snap connection between the valve and float, controlled by said float for controlling the steam pressure supply line, the steam line for the controlled tank and the exhaust line, thereby supplying water to or from the controlled tank and to the boiler. 40
9. In a water supply system for steam boilers, the combination of a controlled tank and a controlling tank, a steam line and connections for supplying steam pressure to the controlling tank, an exhaust line between the controlling tank and the atmosphere, a steam line for the controlled tank, a feed water pipe between one of said tanks and the boiler, a float connected with the controlling tank and the exhaust line, thereby supplying water to or from the controlled tank and to the boiler. 45

In testimony whereof, I have signed my name to this specification.

OSCAR H. LUDEMAN.
